(57) **CLAIM**

The ornamental design for a drawer unit, as shown and described.

DESCRIPTION

FIG. 1 is a perspective view from above of a first embodiment of a drawer unit showing my new design;

FIG. 2 is a perspective bottom view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of the drawer unit shown in an alternate conuguration in a semi opened position, with an inner container sliding out of its housing;

FIG. 10 is a perspective view of the drawer unit shown in another alternate conuguration in a fully opened position, showing the inner container in its entirety;

FIG. 11 is a perspective bottom view thereof;

FIG. 12 is a front view of the inner container of the first embodiment of the drawer unit, shown separate from the housing to show aspects of the design that are not visible when combined;

FIG. 13 is a back view thereof;

FIG. 14 is a left side view thereof;

FIG. 15 is a right side view thereof;

FIG. 16 is a top view thereof;

FIG. 17 is a bottom view thereof;

FIG. 18 is a perspective view of a second embodiment of the drawer unit;

FIG. 19 is a perspective view of the housing with a track area labeled as 21 and further enlarged in FIG. 21;

FIG. 20 is a perspective view of the inner container with a track insert area labeled as 22 and further enlarged in FIG. 22;

FIG. 21 is an enlarged perspective view of area 21 in FIG. 19; and,

(Continued)

FIG. 22 is an enlarged perspective view of area 22 in FIG. 20.

The broken lines encircling portions of the drawer unit in FIGS. 19 and 20 and shown in the enlarged views in FIGS. 21 and 22 form no part of the claimed design.
